(57) **CLAIM**

The ornamental design for a heart shaped hair clip, as shown and described.

DESCRIPTION

FIG. 1 is a perspective view of a heart shaped hair clip in a closed position according to the present design.

FIG. 2 is a top view of the design in a closed position.

FIG. 3 is a bottom view of the design in a closed position.

FIG. 4 is a rear view of the design in a closed position.

FIG. 5 is a front view of the design in a closed position.

FIG. 6 is a left side view of the design in a closed position; and,

FIG. 7 is a right side view of the design in a closed position. The broken lines in the drawings depict portions of the heart shaped hair clip that form no part of the claimed design.
